UNITED STATES PATENT OFFICE.

JOHN L. HALL, OF SCHENECTADY, NEW YORK, ASSIGNOR TO GENERAL ELECTRIC COMPANY, A CORPORATION OF NEW YORK.

AUTOMATIC STARTING-RHEOSTAT.

No. 825,272.

Specification of Letters Patent.

Patented July 3, 1906.

Application filed August 15, 1902. Serial No. 119,696.

To all whom it may concern:

Be it known that I, JOHN L. HALL, a citizen of the United States, residing at Schenectady, county of Schenectady, State of New York, have invented certain new and useful Improvements in Automatic Starting-Rheostats, of which the following is a specification.

This invention relates to rheostats for starting electric motors; and its object is to so construct the rheostat that it will automatically actuate the switch-arm and cut out the resistance when the line-switch is closed, and then automatically reset the parts which actuate the switch-arm, so that when the latter is released by a no-voltage electromagnet the device will be ready to operate when the line-current is restored, but no energy will be consumed by the actuating parts except during the short time they are moving the switch-arm.

In carrying my invention into effect I provide an electromagnet for operating the parts which actuate the switch-arm and a switch in circuit therewith, which is automatically opened at the end of the travel of the switch-arm and is closed by the return of the switch-arm to the "off" position upon its release by the underload-magnet.

30 In the accompanying drawings, Figure 1 is a front elevation of a starting-rheostat embodying my improvements. Fig. 2 is a diagram of circuits, showing the application of the rheostat to a shunt-motor.

35 The rheostat switch-arm 1 is pivoted at 2, and makes contact with the contacts 3. It is normally held in the off position by a spring 4. Pivoted on the switch-arm is an armature 5, adapted to coat with a no-voltage or 40 underload release-electromagnet 6 in series with the field-coil 7 of the electric motor, whose armature 8 is in series with the resistance-coils 9, connected with the contacts 3.

In order to automatically actuate the 45 switch-arm and cut out the resistance from the motor-armature circuit when the line-switch 10 is closed, there is pivoted at 2 a rocker having an arm 11, lying behind the

switch-arm 1 and carrying a stiff spring 12, whose free end is adapted to bear against the 50 back of the switch-arm.

Mounted on the base 13 is solenoid 14, whose core 15 is suitably connected with the rocker to rock the same on its pivot. A switch-lever 16, closing on a contact 17, is in 55 circuit with the solenoid across the mains 18. The connection between the core 15 and the rocker is preferably a toggle composed of a link 19, pivoted at one end to the arm 11 and at the other end to a second link 20, whose 60 further end is hinged to the base at 21. The core 15 is connected by a link 22 with the link 19, and the solenoid is supported on a hinge 23.

A spring 24 tends to move the toggle in opposition to the attraction of the solenoid. 65 The movement of the rocker is regulated by a dash-pot 25, whose plunger is connected with an arm 26 on the rocker. A finger 27 on this arm carries a pin, as shown, on which is an insulating-bushing, which strikes the end of the 70 switch-lever 16 just before the rocker stops moving, and thus open-circuits the solenoid. The switch-arm 1 has an extension 28, also carrying a pin, as shown, on which is an insulating-bushing, which closes the switch-lever 75 16 when said switch-arm goes to the off position.

The operation of the device is as follows: When the line-switch 10 is open, the parts stand as shown in Fig. 2, the switch-arm 1 being on the first contact of the resistance, the rocker tilted to the left, the toggle flexed, and the switch-lever 16 closed on its contact 17. To start the motor, it is merely necessary to close the line-switch 10, thus energizing the 85 field-coil 7, the release-magnet 6 in series therewith, the armature 8 through the resistance-coils 9, and the solenoid 14, which by attracting its core 15 straightens out the toggle and causes the rocker-arm 11 to push 90 the switch-arm 1 along the contacts 3 until the armature 5 strikes the magnet 6, and the switch-arm is magnetically held in this "full-on" position. (See Fig. 1.) The spring 12 allows the rocker to continue its movement 95 after the switch-arm has reached its maxi-

2
mum travel, and by means of the finger 27 the switch-lever 16 is opened and the circuit of the solenoid 14 is broken. The spring 24 at once flexes the toggle, returning the rocker to the position shown in Fig. 2, but the switch-arm 1 remains held by the magnet 6. When the line-switch is opened or the current fails, the switch-arm is released and its spring 4 returns it to the off position, where the projection 28 strikes the switch-lever 16 and closes it. The parts are then restored to the position shown in Fig. 2, ready to operate when the line-switch is again closed.

What I claim as new, and desire to secure by Letters Patent of the United States, is—

1. In an automatic starting device for electric motors, a resistance arranged in the armature-circuit of the motor, a series of contact-surfaces connected therewith, a contact device movable over said surfaces to increase and decrease the resistance in the armature-circuit, an electromagnetic controlling device arranged to move said contact device to cut resistance out of the armature-circuit, an independent circuit including the coils of said controlling device, means for automatically interrupting said latter circuit when the resistance has been cut out of the armature-circuit, and electromagnetic means arranged permanently in series with the field-circuit of the motor, for holding said contact device in position with the resistance out of the armature-circuit.
2. In an automatic starting device for electric motors, a resistance arranged in the armature-circuit of the motor, a series of contact-surfaces connected therewith, a contact device movable over said surfaces to increase and decrease the resistance in the armature-circuit, a solenoid having a core operatively connected to said contact device and adapted, when the solenoid is energized, to move said contact device to cut the resistance out of the armature-circuit, an independent circuit including the coils of said solenoid, means for automatically interrupting said latter circuit when the resistance has been cut out of the armature-circuit, and an electromagnet having its coils included permanently in series with the field-circuit of the motor and arranged to hold said contact device in position with the resistance out of the armature-circuit.

3. A rheostat having contacts connected to resistances, a switch-arm co-operating with the contacts, a solenoid for operating the switch-arm in one direction automatically, a spring for operating the arm in the other direction, and means for automatically cutting out said solenoid when the arm has reached the limit of its travel in one direction.

4. The combination with the switch-arm

of a starting-rheostat, of a solenoid for operating the same automatically, a spring strained in operating the arm, and means for automatically cutting out said solenoid when the arm has reached its position of maximum travel.

5. The combination with a starting-rheostat having a pivoted switch-arm, of a solenoid for actuating said switch-arm automatically when the circuit is closed, and a magnet for holding said arm at its maximum travel.

6. The combination with the switch-arm of a starting-rheostat, of a solenoid for operating the same automatically, means for automatically cutting out said solenoid when the arm has reached its position of maximum travel, means for holding the arm in said position, and a spring to retract the arm when released.

7. The combination with a rheostat having a pivoted switch-arm, of a pivoted rocker movable independently of said arm for actuating the arm, a solenoid for operating said rocker when the main circuit is closed, and means independent of the solenoid for returning the arm to its original position.

8. The combination with a rheostat having a pivoted switch-arm, of a pivoted rocker for actuating said arm, a solenoid for operating said rocker when the main circuit is closed, a spring strained in operating the arm, and means for returning the rocker to its original position independently of the switch-arm when the solenoid is open-circuited.

9. The combination with a rheostat having a pivoted switch-arm, of a pivoted rocker for actuating said arm, a toggle connected with said rocker, a solenoid for operating said toggle, and means for holding the arm in the position of maximum travel.

10. The combination with a rheostat having a pivoted switch-arm, of a pivoted rocker for actuating said arm, a solenoid for operating said rocker, and a switch-lever in circuit with said solenoid and controlled by said rocker.

11. The combination with a rheostat having a pivoted switch-arm, of a pivoted rocker provided with a spring bearing against said arm, a solenoid for actuating the rocker, a magnet for holding the arm at its maximum travel, and a switch-lever in circuit with the solenoid and adapted to be opened by the rocker after the arm has stopped.

12. The combination with a rheostat having a pivoted switch-arm, of a pivoted rocker provided with a spring bearing against said arm, a solenoid for actuating the rocker, a magnet for holding the arm at its maximum travel, and a switch-lever in circuit with the solenoid and adapted to be opened by the

rocker after the arm has stopped and to be closed by the switch-arm when the latter returns to the "off" position.

13. The combination with a rheostat having a pivoted switch-arm, of a pivoted rocker for actuating said arm, a solenoid for operating said rocker when the main circuit is closed, means for holding the arm at its position of maximum travel, means for returning the rocker to its normal position when the

solenoid-circuit is opened, and means for returning the switch-arm to the "off" position when the main circuit is opened.

In witness whereof I have hereunto set my hand this 13th day of August, 1902.

JOHN L. HALL.
